F. W. STANLEY.
AUTOMATIC IRRIGATION NOZZLE.
APPLICATION FILED JAN. 31, 1917.

1,226,137.

Patented May 15, 1917.

Frederick W. Stanley,
Inventor:
Francis J. Caffey,
attorney.

UNITED STATES PATENT OFFICE.

FREDERICK W. STANLEY, OF WASHINGTON, DISTRICT OF COLUMBIA.

AUTOMATIC IRRIGATION-NOZZLE.

1,226,137.

Specification of Letters Patent. Patented May 15, 1917.

Application filed January 31, 1917. Serial No. 145,811.

(DEDICATED TO THE PUBLIC.)

To all whom it may concern:

Be it known that I, FREDERICK W. STANLEY, a citizen of the United States of America, and an employee of the Department of Agriculture of the said United States, residing in the city of Washington, District of Columbia, (whose post-office address is Washington, District of Columbia,) have invented a new and useful Improvement in Automatic Irrigation-Nozzles.

This application is made under the act of March 3, 1883, chapter 143 (22 Stat., 625), and the invention herein described and claimed may be used by the Government of the United States, or any of its officers or employees, in the prosecution of work for the Government, or any person in the United States, without payment to me of any royalty thereon.

My invention relates to irrigation nozzles which are adapted, under water pressure, automatically to assume various positions.

The object of my invention is to provide an irrigation nozzle simple in construction and easy of operation, and one which is specially designed automatically to assume various positions while spraying a given plot of ground so as to irrigate a large area without moving said nozzle to another position in the field.

The object, characteristic features, and scope of my invention will be more readily understood from the following description taken in connection with the accompanying drawing, wherein:

Figure 1 is a perspective view of the nozzle;

Fig. 2 is a longitudinal sectional view, and

Fig. 3 is a side elevation looking toward the ratchet member.

Referring to the drawings, A represents a nozzle standard connected with a water main or other convenient source of water supply. A cylinder, B, is secured to the pipe, A, in any suitable manner, or said cylinder may form an integral part of said pipe. An opening is cut in said pipe and one in said cylinder. These openings are designated C, and are cut opposite each other in said mentioned parts for providing means by which water may pass from the pipe, A, into the cylinder, B, for effecting the purpose hereinafter specified. Adjusted in said cylinder, B, is a plunger, D, having secured thereto a pis-

ton rod, E, passing through a spring, F, 55 which is arranged in operative position between said plunger and the top of cylinder B.

To piston rod, E, is connected a second rod, G, which engages the notches, H, of the ratchet wheel, I, which is conveniently attached by suitable means to the water supply pipe, A. Guide rods, J, secured to the pipe, A, serve to keep the rod, G, in proper working position. Nozzle head, K, having 60 a plurality of apertures, L, cut in the upper end, is adjusted to the supply pipe, A, by means of the rod, M, in such a manner as to allow the nozzle head, K, to assume various positions. Securely attached to the nozzle head, K, is the projection, N, to which is attached the rod, O, which in turn is attached to the projection, P, on the ratchet wheel, I.

In practising my invention, the water is admitted under pressure through the supply pipe, A. Part of the water will pass through the aperture, C, into the cylinder, B, the pressure being communicated to the plunger, D, (the plunger being down), which pressure serves to raise the plunger, D, carrying with it the piston rod, E, and the rod, G. The rod, G, engaging the notches, H, on being raised, serves to turn the ratchet wheel, I, a short distance. The ratchet wheel, I, is oblong, with the notches, H, 85 shorter in the center than near the ends. The rod, O, being attached to the ratchet wheel, I, by means of the projection, P, and to the nozzle head, K, by means of the projection, N, communicates the movement of 90 the ratchet wheel, I, to the nozzle head, K, which tends to cause the nozzle head, K, to take various positions. The water under pressure through the pipe, A, passes through the apertures, L, in the form of a spray. 95 The position of the nozzle head, K, is constant after the water is once turned on, until the water is momentarily shut off, which shutting off serves to relieve the pressure, which in turn allows the spring, F, to carry 100 the plunger, D, down and allows the rod, G, to engage another notch, H, in the ratchet wheel, I. The water being again turned on, the pressure through the plunger, D, the rod, G, the ratchet wheel, I, and the rod, O, 105 serves to cause the nozzle head, K, to assume a slightly different position. The position of the nozzle head, K, can be changed

as often as desired by momentarily shutting off the water, which shutting off and again turning on cause the position of the nozzle head, K, to assume a slightly different position. The oblong shape of the ratchet wheel, I, and the different lengths of the notches, H, give slower action when the nozzle head, K, is nearing the perpendicular, thus giving better distribution.

10 It is also claimed that this device can be used to oscillate spray heads of various designs, being especially useful for oscillating a long, horizontal pipe that is supported by posts or cables at a convenient height 15 above the ground surface, this pipe bearing nozzles at convenient intervals. In such an irrigation device, spray head, K, bearing small apertures, L, would be replaced by a long pipe that would oscillate about the 20 fixed part, A. The connecting pin, M, would be replaced by some common form of turning union, and nozzles, K, would be set 3 to 4 feet apart, the nozzles or apertures throwing streams in parallel lines.

25 From the foregoing, it is thought that the construction, operation and many advantages of the herein described invention will be apparent to those skilled in the art, without further description, and it will be understood that various changes in the size, 30 shape, proportion, and minor details of con-

struction may be resorted to without departing from the spirit or sacrificing any of the advantages of the invention.

Having thus described my invention, I claim:

1. In an irrigation device, the combination of a supply pipe, a nozzle movably connected thereto, a cylinder in communication with said supply pipe, a piston in said cylinder, a rod connected to said piston, a ratchet wheel connected to said nozzle and adapted to be engaged by said rod so that movement of the piston is communicated through said ratchet wheel to said nozzle. 45

2. In an irrigation device, a movable nozzle, a cylinder, a piston therein, a supply pipe in communication with said nozzle and said cylinder, and connections between said nozzle and said piston including a series of rods and a ratchet wheel, the piston adapted to be moved by turning on and off the water to the supply pipe to change the position of said nozzle. 50

In testimony whereof, I affix my signature in the presence of two subscribing witnesses.

FREDERICK W. STANLEY.

Witnesses:

FRED L. WHAM,
ARTHUR H. FAST.
